UNITED STATES PATENT OFFICE.

STEPHEN M. CRETEAU, OF PROVIDENCE, RHODE ISLAND.

DESIGN FOR A STICK-HANDLE FOR CANES, &c.

SPECIFICATION forming part of Design No. 19,213, dated July 23, 1889.

Application filed June 15, 1889. Serial No. 314,498. Term of patent 7 years.

To all whom it may concern:

Be it known that I, STEPHEN M. CRETEAU, a citizen of the United States, residing at Providence, in the county of Providence and State of Rhode Island, have invented and produced 5 a new and original Design for Stick-Handles for Canes, Umbrellas, &c., of which the following is a full, clear, and exact description, reference being had to the accompanying drawings, forming part of this specification.

Figure 1 is a view of the head of a stick used for canes and umbrellas, into the top of which an ornamental cylindrical case is inserted, as is indicated in broken lines. Fig. 2 15 is a top view of the end of the stick, clearly illustrating my design.

The leading features of my design consist in the ball-shaped head of a cane, umbrella, or other stick having a flattened end, a circular disk covered with a number of semi-globular protuberances placed in radial lines 20 from the center of the disk, a circular semi-

spherical depression forming the center of the disk, and a raised rim surrounding the disk.

25

A is the ball-shaped head of a cane, umbrella, or other stick.

30

B is the flattened end of the head A.

C is the raised rim projecting from the edge of a circular disk.

35

D is the circular disk.

E are the semi-globular protuberances arranged in lines radial from the center.

F is the semi-spherical depression in the center of the disk.

Having thus described my new and original design, what I claim is—

The design for the shape and ornamentation of cane and umbrella handles, as herein described and shown.

STEPHEN M. CRETEAU.
